HOOD LATCH

Frank A. Falk, Stacyville, Iowa, assigner to Chicago Forging & Manufacturing Co., Chicago, Ill., a corporation of Illinois

Application January 2, 1932. Serial No. 584,461

1 Claim. (Cl. 292—218)

My invention relates to an improvement in automobile hood latches and is particularly adaptable to employment with multiple hinge hood closures for automobiles. One object is the provision of such a device which shall include an exterior handle and interior latching means positioned within the hood closure. Another object is the provision of a device which shall include a single exterior handle whereby a plurality of interior latching means may be moved into and out of securing engagement with a keeper or keepers. Other objects will appear from time to time in the course of the specification and claim.

15 I illustrate my invention more or less diagrammatically in the accompanying drawing, wherein—

Figure 1 is a side elevation;

Figure 2 is a partial interior elevation on an enlarged scale;

Figure 3 is a section on the line 3—3 of Figure 2;

Figure 4 is a section on the line 4—4 of Figure 2; and

25 Figure 5 is a view similar to Figure 4 with parts in unlocked position.

Like parts are indicated by like symbols throughout the specification and drawing.

Referring to the drawing, A generally indicates 30 a portion of the automobile frame, A¹ is the radiator, A² is the lower hinge member of the automobile closure being hinged to the upper member A³ which is hinged to the automobile as at A⁴. A¹¹ indicates the dash or cowl.

35 Positioned within said closure and spaced more or less therewithin are the keeper brackets generally indicated as B which include a bottom flange B¹, an upwardly extending portion B² and a hook portion B³ inclined downwardly and outwardly toward the inner face of the hood closure. The bracket or keeper so formed may be secured to the frame by any suitable securing means. I illustrate the bolt B⁴ with the nut B⁵.

40 Rotatably mounted upon the inner face of the closure, in a generally horizontal position, is the rock shaft or rod generally indicated as C. I illustrate it as including two end sections C¹ slightly inclined in relation to each other which are connected by a handle portion C². The handle portion C² is positioned exteriorly of the closure, the sections C¹ being connected to the handle portion proper by loops or bends C³ positioned in and passing through the aperture C⁴ in the closure. C⁵ indicates bearing brackets for the opposite ends of the sections C¹. As will be clear

for example from Figures 3, 4 and 5 the brackets C⁵ extend inwardly a substantial distance from the inner face of the closure. The ends of the sections C¹ have bends C⁶ terminating in recurved portions C⁷. The portions C⁶ and C⁷ together 60 form cranks adapted for locking engagement with the hook portions B³ of the keepers. It will be noted, as in Figures 3 and 4, that when the device is in locking position the axes of rotation of the end portions C¹ of the rod C are located 65 inwardly of the keeper hooks B³, the crank portion being therefore inclined upwardly and inwardly toward the inner face of the closure.

Assume that the device is in unlocking position with the handle C² up, as shown in Figure 5. 70 In such position the crank portions C⁶ C⁷ extend inwardly toward the keeper. When the closure is moved to closing position the portion C⁷ actually engages the keeper, as shown in Figure 5. Upon downward movement of the handle C² the 75 portions C¹ are rotated about axes of rotation passing through the bearings C⁵. The crank portions C⁶ C⁷ are thereby rotated into the position in which they are shown in Figure 4, the portions C⁷ engaging the hook B³ and tending to 80 draw the hood closure downwardly and inwardly, in response to the flexure and torsion of the rod portions C¹.

It will be noted that when the parts are in the unlatched position in which they are shown in 85 Figure 5, the crank C⁶ lies in a plane at an angle of 90 degrees or more from the plane defined by the adjacent portion C¹ of the shaft C as shown in Figure 5. But when the parts are in the latched position in which they are shown in 90 Figure 4, the crank C⁶ lies approximately in the plane defined by the portion C¹. This angular variation is a function of the torsion of the rock shaft C and the flexure of the crank portions C⁶ C⁷. The contacting portion C⁷ of the crank C⁶ 95 passes over center and is locked under tension of the shaft portion C¹ in the latching position. In obtaining this result note that the bearing C⁵ is spaced inwardly from the inner face of the hood A² by a distance greater than the distance 100 between the hood A² and the keeper hook portion B³ when the hood is in latched position. The shaft C, in response to flexure of the portion C¹, tends to draw the lower edge of the hood both downwardly and inwardly when the parts are in 105 the position in which they are shown in Figure 4.

It will be realized that whereas I have described and shown a practical and operative device, nevertheless many changes might be made in the size, shape, number and disposition of 110

parts without departing from the spirit of my invention. I therefore wish my description and drawing to be taken as in a broad sense illustrative and diagrammatic rather than as limiting me to my specific showing.

I claim:

In a latching device for the multiple hinge closure of an automobile hood, which includes a plurality of keepers positioned within the hood closure, a rod rotatably mounted upon the inner face of the closure for rotation about a generally horizontal axis, cranks associated with the opposite ends of said rod, and adapted for operative engagement with said keepers, and means for

rotating said rod, including an exterior handle formed integrally with said rod, the closure being apertured to permit the extension of said handle therethrough, the portions of the rod at opposite sides of said handle being inclined somewhat in relation to each other, said device including bearing means for the ends of said rod, said bearing means defining axes of rotation at an angle to each other, the intermediate portion of the rod adjacent its center approaching more closely to the inner face of the closure than the portions of the rod which engage said bearings.
